FOOTWEAR CHAIN

William A. Kniseley, Hunters, Wash.

Application April 20, 1934, Serial No. 721,585

3 Claims. (Cl. 36—7.6)

The invention relates to an anti-skid device for footwear and more especially to footwear chains.

The primary object of the invention is the provision of a device of this character, wherein the same involves the use of chains to be worn by footwear to prevent skidding or slipping when traveling over ice, wet or slippery surfaces, and without discomfort to the user.

Another object of the invention is the provision of a device of this character, wherein the construction thereof is novel to assure the fitting of the same upon footwear, as well as removal, with dispatch, and when upon the footwear will avoid slipping or sliding when treading wet, icy or slippery surfaces.

A further object of the invention is the provision of a device of this character which is simple in construction, thoroughly reliable and efficient in its purpose, durable, and inexpensive to manufacture.

With these and other objects in view, the invention consists in the features of construction, combination and arrangement of parts as will be hereinafter more fully described in detail, illustrated in the accompanying drawing, which discloses the preferred embodiment of the invention, and pointed out in the claims hereunto appended.

In the accompanying drawing there is illustrated in perspective a boot, showing the device constructed in accordance with the invention applied thereto.

Referring to the drawing in detail, A designates generally, by dotted lines, a boot which may be either a shoe, gaiter, overshoe rubber or the like, and is illustrated merely for the purpose of showing the application and the wear of the device constituting the present invention and hereinafter fully described.

The device comprises a series of sole tread chains 1, 2 and 3, respectively, and also a series of heel tread chains 4 and 5, respectively, the chain 1 being carried over the toe end of the footwear, while at opposite sides of the latter and connected with this chain 1 are the forward ends of upper and lower side chains 6 and 7, respectively, these having the loops 8 and 9 about the heel portion of the boot. The chains 6 and 7 at opposite sides of the footwear have the portions 10 of the chains 2 and 3 linked therewith, while the chains 7 have the chains 4 and 5 at the portions 11 linked therewith. These chains 1, 2 and 3 of one series and 4 and 5 of the other series are properly spaced apart and disposed trans-

versely of the sole and heel of the footwear and function as anti-skids therefor.

The chain 8 at one side of the footwear has arranged therein a releasable hook 12 for the opening of the device to permit the application to the footwear or its removal therefrom, the hook 12 being located at one side of the footwear in the vicinity of the heel end of the same.

Connected with the chain 8 are the spaced arch chains 13 and 14, respectively, these bridging the arch portion of the footwear and being properly spaced from each other. Connected with the chains 1, 2 and 3 and centrally located in the longitudinal direction of the footwear is the retaining chain 15 which prevents the spreading 15 apart of these chains 1, 2 and 3 at the sole area of the footwear, and likewise connecting the chains 4 and 5 is the retaining chain 16 which is centered and longitudinally directed with respect to the heel of the footwear and prevents the 20 spreading apart of said chains 4 and 5 when the device is being worn.

At the loops 8 and 9 of the chains 6 and 7 is the heel chain 17, the same being connected to the chains 6 and 7 and vertically disposed to 25 abut the heel end of the footwear and this chain functions to prevent the spreading of the loops 8 and 9 at the heel of the footwear.

It should be apparent that when the device is worn it will function to prevent the skidding or 30 sliding of the footwear when treading icy or slippery surfaces and eliminates the necessity for the use of calks or ice creeper mediums for footwear.

What is claimed is:

1. An article of the kind described comprising 35 a series of spaced sole tread chains, a series of heel tread chains, both series being adapted to be disposed transversely of sole and heel areas of footwear, upper and lower side chains looped about the heel end of the footwear, the series of heel chains being connected to the lowermost side chain, the series of sole chains being connected to both the upper and lower side chains, the outermost of the series of sole chains being carried over the toe of the footwear, and arch chains connected with said upper side chains. 40

2. An article of the kind described comprising 45 a series of spaced sole tread chains, a series of heel tread chains, both series being adapted to be disposed transversely of sole and heel areas of footwear, upper and lower side chains looped about the heel end of the footwear, the series of heel chains being connected to the lowermost side chains, the series of sole chains being connected 50 to both the upper and lower side chains, the out- 55

ermost of the series of sole chains being carried over the toe of the footwear, arch chains connected with said upper side chains, and a releasable hook arranged in the upper side chain.

5. An article of the kind described comprising a series of spaced sole tread chains, a series of heel tread chains, both series being adapted to be disposed transversely of sole and heel areas of footwear, upper and lower side chains looped about the heel end of the footwear, the series of heel chains being connected to the lowermost side chain, the series of sole chains being connected

to both the upper and lower side chains, the outermost of the series of sole chains being carried over the toe of the footwear, arch chains connected with said upper side chain, a releasable hook arranged in the upper side chain, a heel chain connected with the upper and lower side chains at the portions looped about the heel of the footwear, and retaining chains connecting the series of sole and heel chains and disposed centrally in a longitudinal direction of the footwear. 10
